UNITED STATES PATENT OFFICE.

BENJAMIN BARTLY FOSTER, OF RENVILLE, MINNESOTA.

ATTACHMENT FOR CAN CLOSURES.

Application filed May 4, 1922. Serial No. 558,371.

To all whom it may concern:

Be it known that I, BENJAMIN BARTLY FOSTER, a citizen of the United States, residing at Renville, in the county of Renville 5 and State of Minnesota, have invented certain new and useful Improvements in an Attachment for Can Closures; and I do declare the following to be a full, clear, and exact description of the invention, such as 10 will enable others skilled in the art to which it appertains to make and use the same.

This invention relates to an improved attachment for can covers or closures, and it has for its object to generally improve upon 15 attachments of this class by providing one of extreme simplicity and durability which is rigidly connected with the cover, the same extending at right angles from the under side thereof and when in use being embedded 20 in the contents of the can to assist in holding the cover in place and to prevent dust and dirt from collecting on the attachment, whereby to permit clean grease to be applied to and spread on various parts of an 25 automobile.

More specifically speaking, it is an object of the invention to simply use a short metal strip and to bend it between its ends and to secure one of the bent ends to the cover so as 30 to permit the other end to extend at right angles therefrom to serve as an effective paddle for applying and spreading the lubricant.

In the accompanying drawings forming a 35 part of this specification and in which like numerals are employed to designate like parts throughout the same:

Figure 1 is a side elevation, with portions broken away and shown in section, of the 40 improved attachment associated with the cover of a grease can.

Figure 2 is a top plan view of Figure 1.

Figure 3 is a detail perspective of a can 45 cover equipped with the improved attachment.

In the drawings, the letter A represents a cylindrical relatively shallow can which is partially filled with grease G. As is usual, a cover or closure C is removably arranged 50 on the open upper end of the can. It is with this part of the can that the improved invention is associated.

Although the improved attachment could 55 be of some other construction, it preferably comprises a relatively narrow strip of metal

which is bent between its ends as at 1 to provide angularly disposed portions 2 and 3 respectively. The first named portion 2 is riveted or otherwise rigidly secured to the underside of the cover adjacent the rim thereof. The portion 3 of strip constitutes what may be conveniently termed a paddle and this portion of the strip is considerably long when compared to the depth of the can so that when the cover is in place, the free end 60 of the strip extends into close spaced relation to the bottom of the can. Hence, this portion of the attachment is embedded in the grease and serves to maintain the cover in place and a quantity of the grease adheres 65 thereto so that when the cover is removed the paddle can be used for spreading or smearing the lubricant on the desired place of deposit.

In use, the cover is grasped and removed 70 and is held in the hand while the grease is spread or applied to the various parts as is done with the usual wooden paddle commonly used by automobile owners and repair men.

From the foregoing description it will be seen that I have evolved and produced an extremely novel and practical attachment which can be conveniently used for spreading and applying a lubricant to various 75 parts of a machine without requiring soiling of the users' hands. Thus, the invention is very desirable for automobile tourists' use. Furthermore, by rigidly and permanently 80 securing the spreader to the can cover, the latter can be replaced after use and dust and dirt will be prevented from depositing on the spreader. Hence, when the spreader is again used, the grease will be clean and free 85 from detrimental particles such as become mixed with it when following the old method of spreading the grease with a supplemental paddle or the like. If desired, the spreader portion of the attachment can be well used for cutting the grease if it becomes 90 hard and difficult to remove from the can in cold weather. It is obvious that to do this, the cover may be grasped and rotated to move the spreader in a circular 95 manner in the grease. The foregoing and other features and advantages of the invention have doubtless been made clear from the description and drawing. Therefore, a more lengthy and detailed description will 100 not be entered.

Within the scope of the invention as claimed, slight minor changes may be resorted to as is well understood.

I claim:—

- 5 An attachment for can covers or the like comprising a strip of metal bent between its ends to provide right angularly disposed portions, one of said portions being intended to be connected to the underside of the cover

so that the other portion extends at right angles from said cover, said last named portion constituting a spreader or paddle with which the lubricant can be spread or applied to the desired parts of machinery.

In testimony whereof I have hereunto set 15 my hand.

BENJAMIN BARTLY FOSTER.
